Primary Examiner — Jack Reickel*Assistant Examiner* — Russell Carnell Smith, Jr.(57) **CLAIM**

The ornamental design for a support for computer terminal, as shown and described.

DESCRIPTION

FIG. 1 is a top, rear and right side perspective view of a support for computer terminal showing my new design; FIG. 2 is a top, front and right side perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; FIG. 8 is a bottom plan view thereof; FIG. 9 is an enlarged view of portion 9 in FIG. 1; FIG. 10 is a top, rear and right side perspective view showing the support for computer terminal in a first state of use; and, FIG. 11 is another top, rear and right side perspective view showing the support for computer terminal in a second state of use. The broken lines in the drawings illustrate portions of the support for computer terminal which form no part of the claimed design.

1 Claim, 11 Drawing Sheets(56)
